Primary Examiner — Mary Ann Calabrese*Assistant Examiner* — Harper E Comstock(74) Attorney, Agent, or Firm — CANTOR COLBURN LLP(57) CLAIM

The ornamental design for a mattress cover, as shown and described.

DESCRIPTION

The FIGURE is a plan view of a mattress cover for a mattress showing my new design.

The broken lines represent features of an exemplary mattress that form no part of the claimed design. The dash-dot broken lines depict boundaries of the mattress cover that form no part of the claimed design.

1 Claim, 1 Drawing Sheet(56)
